By

F. V. Winters.

Attorney

Inventor:

Hans P. Nelson.

UNITED STATES PATENT OFFICE

HANS P. NELSON, OF GRANTWOOD, NEW JERSEY

PONY POLO MALLET

Application filed August 22, 1931. Serial No. 558,813.

The subject-matter of the present invention relates generally to mallets and the improvements are directed to a novel form of head-structure embodying a protected and 5 moisture-proof core.

Primarily, the object of the invention resides in the production of an article of the above-mentioned character comprising a specially treated core, formed from wood, or the 10 like, said core being encased by material impervious to moisture, thereby preventing splitting or checking of said core.

Another object is to provide novel plug means adapted to be treated and secured to 15 the ends of an encased core whereby the admission or penetration of moisture to said core will be positively precluded.

Still another object of the invention is to 20 provide means for checking the entrance of moisture at the junction of the head portion and the usual handle, said means being somewhat elastic and adapted to embrace a portion of said handle and to overlie the projected portion of the socketed section of said 25 handle in the head and the adjacent portion of said head, thus serving to shed the water or moisture from this connective point and to prevent seepage to the socketed portion.

The invention is further featured by its 30 simplicity in construction of the article and the production of a mallet that will give long and satisfactory service.

With these objects in view, together with others which will appear as the description 35 proceeds, the invention resides in the novel formation, combination, and arrangement of parts, all as will be described more fully hereinafter, illustrated in the drawing, and particularly pointed out in the claims.

40 In said drawing:

Figure 1 is an elevation of a polo mallet constructed in accordance with my invention.

Fig. 2 is an elevation of one of the ends of the mallet.

45 Fig. 3 is a central longitudinal sectional view of the mallet with a portion of the handle shown in elevation.

Fig. 4 is a central longitudinal sectional view of the core.

50 Fig. 5 is an elevation, partly in section,

of one end portion of a core showing a formed recess to receive a special plug.

Fig. 6 is an elevation of a plug adapted to be assembled with the portion of the core shown in Fig. 5.

Referring now more in detail to the accompanying drawing, wherein like characters of reference denote similar parts throughout the several views, let A denote generally the head portion of my improved mallet and B the handle adapted to be associated therewith. In the drawing only a portion of said handle B is shown, but it will be understood that said handle will be constructed of suitable material, of requisite length and provided with the usual attachments as is well-known in the art.

Upon inspection of Fig. 3 it will be seen that said head A comprises essentially a core 10, preferably formed from selected and well 15 and fine grained hardwoods, said core being encased by an impervious casing 11, preferably made of celluloid, and adapted to cover the full longitudinal dimension of said core, thus serving to prevent the splitting of the 20 same longitudinally, which frequently occurs when moisture is present in said core. As shown in Fig. 4, said core 10 is provided with recesses 12, for the reception of plugs 25 13, (see Fig. 3), said plugs serving to seal the ends of the head portion or core to prevent the seepage or entrance of moisture to 30 said core, as will presently appear. Said 35 head A is associated with a handle B, as mentioned hereinbefore, and in this connection it will be noted that said core is provided with an angularly disposed opening 14 and that said casing 11 is provided with aligned 40 openings 15 and 16 for the reception of one 45 end of the handle. Again referring to Fig. 5 it will be further observed that one extremity of said handle B is split at 17 for the 50 reception of a wedge 18, the latter serving to slightly spread the end of the handle to 55 assure a snug and tight fit at this point of 60 connection. It will be noted that I have also 65 provided means to protect the joint adjacent 70 the opening 16 and the contiguous portion 75 of the handle, said means being in the form of 80 an elastic sleeve 19, which embraces that por- 85

100

tion of the handle above said opening 16 and which spreads circumferentially about said opening and substantially concentric therewith to positively seal the opening and to prevent the admission of moisture to that portion of the handle embedded in the casing and core.

From the foregoing it will be seen that I have provided a mallet embodying a core 10 suitably sealed and protected from the deleterious effect of moisture and the like. Further, the mallet is of suitable weight and adapted to give long service.

As mentioned hereinbefore, said core 10 is made from suitable fine-grained hardwood, which is first turned to the shape indicated in the drawing and provided with opening 14 and the recesses 12. In this condition the core is rendered moisture proof by boiling 20 with a light oil, such as albolein, to which has been added the proper amount of paraffin, said core being thoroughly impregnated with this material and rendering the same impervious to the absorption of moisture. Next a cylindrical tube of celluloid, previously treated in boiling water, is gently placed over said core and conformed thereto, said tube having been cut approximately one-half 25 an inch longer than the core so that ends 30 thereof will extend beyond the ends of said core a suitable distance. The core and the tube of celluloid are now placed in cold water whereupon the contraction of said celluloid causes the tube to clinch and bind 35 around said core to form the casing 11, thus sealing the encased portion of said core. The plugs 13 are next affixed within the recesses 12, said plugs having been previously treated 40 exteriorly with a celluloid tenacious and liquid substance, and forced into said recesses 12 to assure a moisture proof connection at all 45 points. As shown in Fig. 3 said plugs 13 are screw-threaded and provided with square sockets 13a into which a suitable tool may be 50 inserted to cause the plugs to cut their own threads into the recesses 12. It is obvious that the substance applied to said plugs will fill and close all openings between the core 55 and plugs and provide an air and moisture proof connection at either end of the mallet. It will be appreciated that the plugs may be deprived of their threads and a special plug 20, (see Fig. 6) used instead. In this instance the plug or plugs 20 are treated as before and 60 forced into the recess 21 formed in the end of the mallet 22 shown in Fig. 5. In all other respects the operations are the same.

After the plugs have been suitably affixed, said celluloid casing 11 is trimmed at the ends, finished and rounded over to present its extremities flush with the end faces of said plugs 13 or 20, as shown in Fig. 3. The handle B is next inserted in the openings 14, 15 and 16, as described hereinbefore, and the wedge 18 applied to firmly bind the same

within said openings. As there exists a possibility of seepage around said handle at the opening 16, I provide the rubber sleeve 19 which embraces the handle, as shown, and serves as positive means for checking the entrance of such moisture lingering at or entering thereat. The flaring bottom of said sleeve entirely covers the area surrounding the opening 16 and when said sleeve entirely covers that particular region and is pressed down, its resiliency asserts itself and thus creates a partial vacuum at that point so that no air or moisture can find its way into any opening or joint.

While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

I claim:

1. The herein described process of making a mallet which consists in treating a wooden core in heated oil to render the same impervious to moisture, affixing and shaping a prepared cylinder of celluloid about said core and finally affixing moisture-proof plugs to the ends of said core to seal the connection between said core, said cylinder of celluloid and said plugs.

2. The herein described process of making a mallet which consists in treating a wooden core to render the same impervious to moisture, affixing a prepared cylinder of celluloid about said core and finally affixing moisture-proof plugs to the ends of said core to seal the connection between said core, said cylinder of celluloid and said plugs.

3. A polo mallet comprising a wooden core having its extremities recessed, a celluloid casing embracing said core and having its ends overhanging the recessed extremities of said core, and plug means fitted into the recesses of said core and filling the spaces beneath the overhanging ends of said casing to seal the ends of the mallet.

4. A polo mallet comprising a core having an angularly disposed opening, a casing embracing said core and having openings aligned with the opening in said core, means for sealing the exposed ends of said core, an handle insertible in the openings in said core and casing, and an elastic sleeve embracing that portion of the handle above one of the openings in said casing, and contacting with said casing about said opening to seal the same and to prevent the admission of moisture to that portion of the handle embedded in the casing and core.

In testimony whereof I affix my signature.
HANS P. NELSON.
